COMBINATION POCKET LIGHTER AND
CIGARETTE INCLOSING DEVICEWilliam Alexander Dion, Plainville, Mass., as-
signor to Evans Case Company, North Attle-
boro, Mass., a corporation of Massachusetts

Application January 15, 1930, Serial No. 420,861

6 Claims. (Cl. 206—41.4)

This invention relates to devices for inclosing cigarettes and the like and particularly to such devices in which there is incorporated a lighter.

One of the objects of the invention is to provide a simple and compact article of this class which may be conveniently carried in the pocket. Another object is to provide an article of the above nature which is efficient and dependable in action and may be economically produced. Other objects will be in part obvious and in part pointed out hereinafter.

The invention accordingly consists in the features of construction, combination of elements and arrangements of parts as will be exemplified in the structure to be hereinafter described and the scope of the application of which will be indicated in the following claims.

In the accompanying drawing, in which is shown one of the various possible embodiments of this invention:

Fig. 1 is a perspective view,

Fig. 2 is a sectional view taken substantially on the line 2—2 of Fig. 1,

Fig. 3 is a similar view taken substantially on the line 3—3 of Fig. 1,

Fig. 4 is a sectional view on the line 4—4 of Fig. 3, and

Fig. 5 is a similar view on the line 5—5 of Fig. 1.

Similar reference characters refer to similar parts throughout the several views of the drawing.

Referring to the drawing there is shown a top frame 10 which is adapted to fit about the upper end of a package of cigarettes. This frame comprises a depending flange 11 extending about the sides and one end of the package and a corresponding inturned flange 12.

Secured within this frame 10 is a resilient wire member consisting of parallel side sections 13 connected at one end by a transverse section 14, the forward ends of the sections 13 forming depending loops 15 connected at their rear end by a transverse section 16.

A cover member 17 is hingedly mounted at its rear end on the transverse section 14 of the wire member and the marginal portions along the sides of this cover member are adapted to rest on the corresponding flanges 12 of the frame 10 when the cover is in closed position. At the forward end of the cover member is a depending flange 18 similar to the flange 11 on the frame 10 and this flange is adapted to enter between the free front ends of this frame as the cover is lowered and upon the completion of the closing acts with the frame to completely envelope

the upper end of the package of cigarettes. In the construction shown this flange 18 is formed on one end of a plate 19 soldered or otherwise fastened to the under face of the cover member 17.

To the under face of the cover member 17 at its rearward end is secured by solder or otherwise a plate 21 from which are struck loops 22 which envelope the transverse section 14 of the wire member to form the hinge connection between the cover and the frame. A portion of this plate 21 extends downwardly from the cover member and is provided at its lower edge with a loop 23 which envelopes the transverse section 16 of the resilient member. Lifting of the cover causes the plate 21 to swing inwardly about the axis of the section 14 and to carry with it the rear portion of the loops 15 against the resistance of the spring metal or, in other words, this movement of the cover compresses these loops as indicated in dot in Fig. 3. On release of the cover, the resiliency of the loops automatically causes the cover to close. In the same manner, manual compression of the loops causes the cover to be lifted, and upon release of the pressure the cover is automatically closed. Normally these loops act to hold the cover tightly closed. This pressing action to lift the cover may be accomplished by grasping the package in one hand and squeezing the same between the fingers and thumb sufficiently to cause the rear portion of the loop to be drawn toward the forward portion. The position of the cover is a function of the angular relation of the hinge loops 22 and 23, and the tension of the loops 15 constitutes spring means to close the cover when it has been opened.

Any tendency of the cigarettes to become jammed in the front end of the package due to the forward movement of the rear portion of the loops and particularly the section 16 during the lifting of the cover is eliminated by the absence of any frame member across the front end of the package. This is due mainly to the fact that the flexible package is permitted to bulge sufficiently through this end to enable the cigarettes to be readily withdrawn. As soon as the pressure is released, the flange 18 on the cover will cause the package to return to its normal form and position and will act to adequately support it at this point.

The central portion of the cover member is cut away to form an opening 24 in which is placed a lighter unit 25 of suitable type. This lighter may be held in place within the opening by solder or in any other convenient manner. Openings 26

and 27 are provided in the bottom of the lighter unit to permit sparking elements and fuel respectively to be inserted in the lighter. These openings may be closed by the usual screw caps or plugs 28 and 29 and convenient access may be obtained thereto when the cover member 17 is in raised position. The lighter construction shown is of the automatic type in which a sparking wheel 30 and snuffer 31 are actuated by manual pressure on an operating lever 32. A burner 33 is normally covered by the snuffer 31 and is provided with a wick 34 extending into the usual fuel receptacle within the body of the lighter.

15 When the device is applied to a package of cigarettes as 35 from which the top has been removed, the loops 15 are slid downwardly and between the side walls of the package and the cigarettes until the upper edge of the package is substantially in contact with the under face of the inturned flanges 12 and between the depending flanges 11 and the wire sections 13.

To actuate the lighter mechanism, the finger piece 32 is depressed, preferably with the thumb, 25 the cigarette package 35 forming a grip for the hand. When the finger piece is depressed, the snuffer 31 rises, and the sparking wheel is rotated, both actions being effected by means of actuating mechanism connected to the finger piece, which actuating mechanism is not shown, 30 as this lighter mechanism per se was, at the date of filing of this application, readily identifiable to all those skilled in this art as a known commercial product. Rotation of the sparking wheel 35 lights the wick 34, which is then uncovered, and to extinguish the flame the finger piece is released, whereupon a spring returns the snuffer 31 and finger piece 32 to the position shown in the drawing.

40 The finger piece 32 is, in this particular embodiment of the invention, journaled at the axis of the sparking wheel 30, and accordingly downward pressure thereof has no tendency to open the cigarette compartment, as the line of pressure passes to the left of the pivot 16. The package may be gripped with the hand, and thereupon the cover member 17 raised by a squeezing action, and allowed to close again by simply releasing the pressure, and without shifting the grip at all 45 (simply moving the thumb up and over the finger piece 32) the wick 34 may be ignited, and also thereafter extinguished by merely relaxing the thumb pressure on the finger piece 32. Thus the device is characterized by finger pressure to 50 open the cigarette compartment, and finger pressure to ignite the lighter, both being returned to normal position simply by relaxing the grip. It will be additionally noted that when the cover 17 is up, as shown in Figure 3, the lighter and fuel tank by reason of gravity tend to keep it open, and the spring pressure of the loops 15 is preferably such that the cover is in substantially neutral equilibrium when the parts are in the position shown in Figure 3 (dotted line position of 55 the cover) so that the cover will stay open with little or no pressure, but a slight inclination or mere movement of the entire device serves to cause the cover to close, the grip being relaxed.

The article is a very compact cigarette container and lighter, by reason of the fact that the cigarettes are disposed vertically therein, and there are no sideways projecting parts to catch in the pocket, the entire device being adapted to fit in a vest pocket. It will be noted that the 60 filling opening 27 and the sparking material open-

ing 26 are readily available when the cover is in the open position, and to avoid spilling fuel on the cigarettes the device may be inverted so that the cover plate 17 is horizontal but with the openings facing upwardly. The device can be held in this 5 position without any effort by reason of the weight of the lighter mechanism and the fuel tank.

When the wick 34 is lit, the flame is well away from the thumb which actuates the finger piece 10 32, and by reason of the height of the burner 33 above the cigarette package 35, the flame is also far removed from the forefinger gripping the cigarette package. The entire article is characterized by ease of operation as it is large enough 15 to be easily gripped with an open and firm grip permitting a strong finger pressure to be exerted against the finger piece 32 (preferably with the thumb as aforesaid), and at the same time the part used as a hand grip is given the additional 20 function of holding the cigarettes.

It will be evident from the foregoing description that the entire device is simple and compact in construction and may be conveniently carried in the pocket. The device is efficient and 25 dependable in action and may be economically produced. While a particular type of lighter unit has been illustrated and described it will be obvious that any other suitable form of lighter construction having the capabilities indicated 30 may be used.

It will thus be seen that there has been provided a device in which the several objects of this invention are achieved and that the entire device is of an essentially practical nature. 35

As many other embodiments may be made of the above invention and as many changes may be made in the embodiment above set forth, it is to be understood that all matter herein set forth or shown in the accompanying drawing is to be 40 interpreted as illustrative and not in a limiting sense.

I claim:

1. In a device of the character described, in combination, a flexible receptacle for cigarettes, 45 a frame member adapted to partially encompass the upper marginal portion of said receptacle, a flat plate constituting a cover for said receptacle and hingedly secured to said frame member, resilient means controlling the position of 50 said plate with relation to said receptacle, a lighter on said plate having filling openings extending through said plate both for pyrophoric metal and for fuel, and closures for said openings. 55

2. In a device of the character described, in combination, a cigarette holder including a pair of spaced loops said loops being disconnected, a hinged element connected to the free ends of said loops, a cover attached to the hinged element, whereby upon compressing the loops in the planes thereof the cover is swung open, and a lighter unit mounted on said cover and including an operating lever actuated by manual pressure at that end of the cover adjacent the free 60 ends of the loops, and having a snuffer and burner at the other end, whereby the device may be grasped with one hand and by a squeezing motion the cover is opened and when the grip is released the cover closes and in such position 65 the finger piece is available for actuation by the thumb without changing the grip. 70

3. In a device of the character described, in combination, means to hold a plurality of cigarettes said means being substantially a rectan- 75

5   gular parallelepiped in outline and being resili-
10   ent and capable of having its back wall com-
      pressed towards its front wall near the top por-
      tions of said walls, a cover for said means com-
      pleting the parallelepiped on top, connections be-
      tween the means and the cover constituting a
      hinge for the cover and so formed that upon
      squeezing the back of the parallelepiped toward
      the front the cover is swung open, the resiliency
      10   of the means urging the cover into closed pos-
      ition, and lighter means carried by the cover and
      including a depressible finger piece at that end
      of the cover at which it is hinged to the means
      and a burner spaced therefrom toward the other
      15   end.

15   4. In a device of the character described, in
      combination, a fuel tank, a cigarette compart-
      ment connected to said fuel tank, a cover for said
      cigarette compartment hinged thereto, a depress-
      20   ible finger piece mounted on said fuel tank, a
      wick extending into said fuel tank, a snuffer for
      said wick connected to be actuated by said finger
      piece, spring means to close said cover, means
      operable by finger pressure for opposing said
      25   spring means, and for thereby effecting opening
      of said cover and acting when released to per-
      mit said spring means to close said cover, and
      spring means opposing depression of said finger
      piece by finger pressure and acting when re-
      30   leased to close said snuffer, said finger piece and
      said finger pressure operable means being adjac-
      ent each other so that the cover may be opened
      by finger pressure and closed again by relaxing
      said finger pressure and said wick may be ignited
      35   by finger pressure without shifting the grip and
      extinguished again by relaxing the pressure.

40   5. In a device of the character described, in
      combination, a handle or grip-like casing mem-
      ber dimensioned to contain cigarettes and to
      lie in and be gripped by the hand, lighter means
      45   supported by said handle-casing member on the
      upper end thereof, said lighter means including
      a manually operable finger piece positioned at
      that end of the upper end of said handle-casing
      member as to be easily reached and operable by
      the thumb when said handle-casing member is
      gripped by the hand, a closure member for said
      handle-casing member and operable into an open
      position with respect to said casing member in

5   a direction away from said handle-casing mem-
      ber and those portions of the hand gripping the
      same, and means responsive to the exertion of
      finger pressure inwardly of said handle-casing
      member for opening said closure member, said
      means being operable without substantially
      10   changing the grip of the hand upon said handle-
      casing member, said casing member including
      means for maintaining said closure member in
      closed relation with respect to said casing mem-
      ber when finger pressure is not exerted on said
      casing member, whereby said casing member may
      be opened to obtain a cigarette, closed after ob-
      taining the cigarette, and the lighter immediate-
      15   ly operated thereafter all by one hand without
      substantially changing the grip on said handle-
      casing member.

6. In a device of the character described, in
      combination, a handle or grip-like casing member
      dimensioned to contain cigarettes and to lie
      in and be gripped by the hand, lighter means
      20   supported by said handle-casing member on the
      upper end thereof, said lighter means including
      a manually operable fingerpiece positioned at
      that end of the upper end of said handle-cas-
      ing member as to be easily reached and operable
      25   by the thumb when said handle-casing member
      is gripped by the hand, a closure member for said
      handle-casing member and operable into an open
      position with respect to said casing member in a
      30   direction away from said handle-casing member
      and those portions of the hand gripping the same,
      and means responsive to the exertion of finger
      pressure upon said handle-casing member for
      opening said closure member, said means being
      35   operable without substantially changing the grip
      of the hand upon said handle-casing member,
      said casing member including means for main-
      taining said closure member in closed relation
      with respect to said casing member when finger
      40   pressure is not exerted on said casing member,
      whereby said casing member may be opened to
      obtain a cigarette, closed after obtaining the cig-
      arette upon the release of the finger pressure ex-
      erted for opening said casing member, and the
      45   lighter immediately operated thereafter all by one
      hand without substantially changing the grip on
      said handle-casing member.

WILLIAM ALEXANDER DION.
